(57) CLAIM

The ornamental design for a kitchen utensil, as shown and described.

DESCRIPTION

The patent or application file contains at least one drawing/ photograph executed in color. Copies of this patent or patent application publication with color drawing(s)/photograph(s) will be provided by the Office upon request and payment of the necessary fee.

FIG. 1 is a perspective view of a first embodiment of a kitchen utensil, showing our new design;

FIG. 2 is a bottom view thereof;

FIG. 3 is a left side view thereof;

FIG. 4 is a top view thereof;

FIG. 5 is a right side view thereof;

FIG. 6 is a back view thereof;

FIG. 7 is a front view thereof;

FIG. 8 is an exploded view thereof;

FIG. 9 is a perspective view of a second embodiment of a kitchen utensil according to the invention;

FIG. 10 is a bottom view thereof;

FIG. 11 is a left side view thereof;

FIG. 12 is a top view thereof;

FIG. 13 is a right side view thereof;

FIG. 14 is a back view thereof;

FIG. 15 is a front view thereof; and,

FIG. 16 is an exploded view.
